UNITED STATES PATENT OFFICE.

HARRY I. ALBRIGHT, OF AKRON, OHIO.

DEVICE FOR ATTACHING LAMPS TO VASES.

Application filed December 26, 1924. Serial No. 758,016.

This invention relates to devices for securing lamps such as electric lamps on vases formed with constricted portions and has for its object the provision of simple inexpensive means for securing a suitable electric lamp and base of standard construction onto any type of vase to convert the latter into a lamp stand.

The foregoing object is accomplished by the construction described below and illustrated in the accompanying drawings, it being understood that the invention is not limited to the specific construction described and illustrated.

18 Of the accompanying drawings:

Figure 1 is an elevation of a vase having a lamp mounted thereon by a device embodying the invention and indicated therein by dotted lines;

20 Figure 2 is a full-size elevation partly in section illustrating the device of the invention with its parts in position for insertion into the vase; and

25 Figure 3 is an enlarged bottom plan, partly in section, of the device as it is shown in Figure 1.

Referring to the drawings, 10 is an ordinary lamp socket having a lamp 11 therein and having a base 12 secured thereon by a 30 nipple 13 threaded into an aperture 14 in socket 10 and retained therein by a set screw 15, the nipple 13 extending through an aperture in the top of base 10 and having a shoulder 16 for clamping it onto a connection 35 17 into which the nipple 13 is threaded.

The connection 17 is threaded into one branch of a T 18, the opposite branch of which has threaded therein a threaded rod or tube 19. The other branch of the T provides an aperture for receiving a conductor cable 20 which is carried into the T through an aperture in base 10 and up through fitting 17 and nipple 13 and connected to the lamp socket 10. On the rod 19 is a nut 21 through opposite sides of which extend pins 22, 22 on which are pivoted arms 23, 23. The arms 23 are formed with flanges 24, 24 formed so as to straddle the nut 21 and by which they are mounted on the nut, the pins

22 being passed through apertures in the flanges and riveted over on their outer ends to secure the arms on the nut. The arms 23 are cut away as at 25, 25 to clear the rod 19. Forced onto the free ends of arms 23 are short pieces of rubber tubing 26, 26 forming 55 cushions adapted to act in the manner of suction cups against the wall of the vase to tightly grip the same.

In use, the device is secured to the socket 10 and base 12 in the manner illustrated. 60 The arms 23 are folded upwardly as shown in Figure 2, the device being then inserted downwardly through the mouth of the vase whereupon due to the action of gravity the arms 23 unfold into the position shown in Figure 1, in which they are limited by engagement with the lower face of the nut. The base 12 is firmly grasped in one hand and the vase is rotated by the other to cause nut 21 to rise on rod 19. This action results 70 in the mouth of the vase engaging the bottom of base 12 and the arms 23 being gripped tightly against the wall of the vase. Thus the lamp is quickly and easily secured on the vase.

75 Modifications of the invention may be resorted to without departing from the spirit thereof or the scope of the appended claim.

What is claimed is:

An electric lamp adapted to be mounted on a vase, said lamp comprising, in combination, an electric light socket and a hollow base therefor, a conductor conduit extending from the socket, a T secured on the lower end of said conduit so that the aligned 85 branches of the T are vertical and the other branch of the T extends laterally therefrom, conductors extending through the lateral branch of the T, the upper of the vertical branches of the T, and the conduit to the 90 socket, a threaded member secured in the lower vertical branch of the T and extending downwardly therefrom, a nut on the member, and arms pivoted on the nut so as to be normally held by gravity in horizontal 95 positions but foldable upwardly to be insertable through the mouth of a vase.

HARRY I. ALBRIGHT.
